MEANS FOR LOCATING A TRAIN AND INSTRUCTING IT TO TAKE A SIDING

Filed Oct. 3, 1927

UNITED STATES PATENT OFFICE

ALLEN B. KENDALL, OF MAYWOOD, ILLINOIS, ASSIGNOR TO ARCHIBALD G. SHAVER, OF CHICAGO, ILLINOIS

MEANS FOR LOCATING A TRAIN AND INSTRUCTING IT TO TAKE A SIDING

Application filed October 3, 1927. Serial No. 223,663.

This invention relates to improvements in means for locating a train and instructing it to take a siding.

When it is necessary for one train, such as a freight train, to take a siding in order that a passenger train, for example, may pass it, and where such passing points are not in accordance with the time card, it is the present general practice for the train dispatcher 10 to issue written orders to the trains concerned to pass at a certain siding. The issuing of these orders consumes considerable time. Usually the orders are given by the dispatcher to local operators who deliver 15 them to the trains, which practice requires the trains to stop or slow down.

Also, in the present railroad practice, if the dispatcher wishes to get the location of a train, he communicates with the local operator 20 at the station near which the train is supposed to be. Often the reply of the operator is that the train has passed by, or it is in sight, or there is no information concerning it; all of which is more or less indefinite. Consequently the train dispatcher 25 is usually not able to figure definitely on close meeting points and considerable time is lost in the movement of the trains over the division.

30 It is the general object of this invention to provide an electrically operated system whereby the dispatcher himself may locate the trains to fix their passing point, and then direct one of them by appropriate signal indication to take the siding at the passing point. This is accomplished without the aid 35 and cooperation of local operators and without delaying the train to receive written orders.

40 Another object of the invention is to provide means enabling the dispatcher to not only locate the train, but also determine its direction and calculate its average speed.

A further object is the provision of means 45 for the display by the dispatcher of a signal directing the train to take the siding.

An additional object is to provide, in such a system, an arrangement of apparatus for exhibiting the "take siding" signal which 50 will allow the display to continue until the

rear end of the train passes the signal, when the display is automatically withdrawn.

Other objects and advantages relate to the saving of time and minimizing of responsibilities of the dispatcher in that, with this system and apparatus for locating a train and giving it a "take siding" signal indication, the dispatcher does not need to withdraw the "take siding" signal as soon as the train for which it is intended has passed, nor be concerned that a following train will accept its indication.

In the accompanying drawing, one embodiment of the invention is represented diagrammatically, and shows a section of railroad, with signals, circuits, relays and other devices.

The train locating and direction indicating means comprises a circuit containing fixed resistances at different points, in series with a battery and an indicating instrument. The fixed resistances are associated with the different track circuit sections in such a way that as the train moves along, one resistance after another is eliminated from or added to the circuit, which causes the reading of the train indicator or indicating instrument in the dispatcher's office to change correspondingly, thus showing the direction and location of the train.

In the diagram, E, E are the rails of the track, divided into sections, S1, S2, S3, etc., each section constituting a track circuit with a battery TB1, TB2, TB3 etc., and a relay T1, T2, T3, etc. SW is the main track switch leading to the siding. H represents one of a series of signals installed on the railroad. TS is a "take siding" signal which for convenience is shown as of the semaphore type and located on the mast with signal H.

R1, R2, R3, etc., are resistances, preferably of equal value, associated with the correspondingly numbered track circuits, as hereinafter explained.

The normal circuit for the train indicator EV, starting from the battery "C" may be traced through conductor 1, and the dispatcher selector line D1 through conductor 2, resistance R1, conductor 3, resistance R2, conductor 4, resistance R3, conductor 5, re-

sistance R4, conductor 6, resistance R5, conductor 7, indicator EV and conductor 8, back to the battery.

Contact 10 of the relay T1 is normally open, as the relay is energized by the battery TB1, but when a train enters the section S1 and short circuits said battery, said contact drops and closes the shunt circuit 11-12 around resistance R1.

10 Relay T2 when de-energized by the entrance of the train into section S2 drops its contact 13 and shunts out resistances R1 and R2 through conductors 14 and 15.

15 Relay T3 in like manner subsequently drops its contact 16 when a train enters section S3, and by means of conductors 5 and 18, short circuits resistances R1, R2 and R3.

20 Relay T4 also drops its contact 17 at a later period and closes local circuit, conductors 6 and 18, cutting out all four resistances, R1, R2, R3 and R4, the resistance R5 remaining in the circuit with the indicator throughout.

25 The train indicator EV is similar to an ammeter, and as the resistance in circuit therewith decreases in the manner just described, the hand of the instrument moves successive steps in the same direction, for example, to the right in the arrangement shown in the diagram where the train is moving from left to right. If the train is moving in the opposite direction, the minimum resistance is in series with the indicator at the outset, said resistance building up by successive steps and causing the indicator hand to move to the left. The indicator, therefore, indicates not only the direction in which the train is moving, but it displays also during the time consumed by the train in passing over a particular section so that the approximate average rate of speed may be determined.

30 In the operation of the system the dispatcher looks at his indicator and if it registers 1, he knows a train is in section S1; if 2 the train is in section S2; etc. Knowing the 35 length of the sections, and observing the time between successive changes of the instrument, he can readily determine the average speed. If the indicator hand moves from 3 to 2 to 1, the dispatcher knows that the train is travelling in the opposite direction from that just assumed.

The means for signalling the train will now be described:

35 SP is a switching relay in which there are the usual electro-magnet 19 and circuit contacts as 20, controlled by 19, and a rotating device or tooth commutator 21, alternately bridging contacts 22 and 23 interposing resistance between the same to open and close the circuit. The arm 24, which is fastened to the armature of relay SP, is controlled by electro-magnet 19 and operates the commutator 21 every time the electro-magnet 19 is energized. As shown in the diagram, con-

tacts 22-23 are bridged by the insulation, and the circuit is open. When 19 is energized, arm 24 steps 21 around so that contacts 22-23 are bridged by the conductor part of 21, closing the circuit. When 19 is again energized the insulating part of 21 is stepped forward so the circuit is opened.

70 SL is a selector like those in general use for train dispatching. When the dispatcher operates the code key corresponding to selector SL, the latter is operated to close its circuit contact 25, and thus close the circuit to the switching relay.

75 Selector SL is energized from a source of energy in the dispatcher's office by being connected across conductors D1 and D2 by conductors 26 and 27.

80 Switching relay SP is energized in a circuit including contact 25 when closed, conductor 28, battery B, conductor 29, coil 19 and conductor 30.

85 Control relay C is of the stick type, that is, it is so designed as to hold itself closed after being energized. It is first energized in a circuit comprising battery A, conductor 90 31, contact 32, conductor 33, magnet coil C, conductor 34, contact 20 closed, conductor 35, contact 22-23 closed and conductor 36. When C is energized it closes its contact 37, sticking itself in a circuit as above except 95 conductor 39, contact 37 and conductor 38, replace contact 20 and conductor 34. Relay C as hereinafter explained is controlled partially by a circuit including the normally open contact 40 and conductors 41 and 42. 100

The circuit for the "take siding" signal TS, as shown, has to be closed to display TS. It comprises battery A, conductors 31 and 43 to any suitable operating means for TS, conductor 44, contact 45 closed and conductor 46. 105

The "take siding" signal TS is located so as to be passed before the switch is reached. It is caused to be displayed by the dispatcher operating the appropriate selector in his telephone selective system. It is also controlled 110 by the track circuit system. It is held displayed until the train for which it is intended has passed by, when the presence of the train on the track causes the signal to be withdrawn. After causing the signal to be displayed, the dispatcher may also withdraw it by again operating the selector.

115 Assuming the train is bound toward X, is in section S1 and the dispatcher wants it to pass another train at X, he operates the selector SL to close its contacts 25 which energizes switching relay SP for a short interval closing contacts 22-23 and 20. The closing of these latter contacts energizes control relay C which causes the "take siding" signal 120 to display. The engineer on seeing the signal immediately prepares to enter the siding through the switch SW.

125 It is important that the conductor at the rear of the train also sees the "take siding" 130

signal displayed. Therefore, as already explained, the "take siding" signal displays till the rear end of the train passes it. This gives the conductor on the rear end of the train ample time in which to see the signal for himself.

Contact 32 opens when the train advances into section S2 and de-energizes relay T2 but it cannot be effective in de-energizing control 10, relay C and thus effecting the withdrawal of "take siding" signal TS till contact 40 in parallel with it, and which is closed as long as the train is in section S1, is opened; and contact 40 cannot open till the train is wholly 15 out of section S1.

In the case of an ordinary "take siding" signal arrangement, the dispatcher being busy might forget to withdraw the "take siding" signal and its message would be transmitted to some train for which it is not intended, causing delay and inconvenience. In the arrangement here shown this cannot happen. After displaying the signal to the train for which it is intended, it is automatically withdrawn by the passing of said train.

If the switch SW is hand operated, the train must stop for a member of the crew to operate it. If the switch is controlled from the train as shown for example in the application for patent Serial #198,824, filed by A. G. Shaver June 14, 1927, or if it is operated by some other agency, the train will proceed into the siding without stopping.

The train indicator system as illustrated is applied to a small portion of a railway line. It should be understood that it may be applied to an entire division. Or it may be applied to a section of line and the indicating instrument E located in a tower or local telegraph office.

The present invention is to be understood as applicable to single as well as double track and in other respects also as not limited to the present disclosure. For example, instead of resistances, a series of batteries may be used in conjunction with corresponding track sections, said batteries being of different voltages to change the reading of the indicating instrument correspondingly, or, if they are of the same voltage, their combined voltages causes a variation in the flow of current to operate the instrument.

What I claim is:

1. The combination with a track having insulated sections, each with a battery and a relay controlled thereby and by the passing of a train, of a series of resistances, each controlled by one of said relays, and an indicating instrument in series with said resistances whereby the latter may be short circuited successively by a moving train to cause a predetermined reading of said instrument corresponding to the location of said train.

2. The combination with a track having in-

sulated sections, each with a battery and a relay controlled thereby and by the passing of a train, of a series of resistances, each controlled by one of said relays, and an indicating instrument in series with said resistances whereby said resistances may be cut out of circuit or cut into circuit by a train moving in one direction or the other, to cause predetermined readings of said instrument corresponding to the location of said train and as 70 an indication of the direction of travel of said train.

3. In a system adapted for determining the location and direction of travel of a railroad train, a circuit, including resistances, a source of energy, an indicating instrument, and track circuit means for shunting the resistances from said circuit to change the readings of said indicating instrument.

4. In a system for indicating the location of a railroad train, the combination of a series of track circuits, each with a relay controlling a circuit contact, and a line circuit comprising a series of resistances, a source of energy and an indicating instrument, said contact operating to shunt out resistances from said line circuit whenever a train is in the track circuit controlling the relay.

5. In a train indicating system, the combination of a circuit comprising a series of resistances, a source of energy, an indicating instrument, and means, controlled by the movement of the train, for shunting said resistances to vary the reading of said indicating instrument.

6. In a train indicating system in combination, a stretch of track for a train, track section circuits in said stretch each including a relay operated by the train, means including said relays for causing the indicating instrument of said system to register increasingly for one direction of movement of the train and to register decreasingly for the opposite direction of movement of said train.

7. An electrical train indicating system comprising a series of track circuits, an indicator circuit comprising a source of current and electrical resistance, and relays controlled by the track circuits and in turn controlling said electrical resistance to vary the amount thereof in said indicator circuit.

8. In an electrical train indicating system the combination of a circuit containing electrical resistance, a source of energy and an indicating instrument, with a railroad track and train operated circuit controlling devices thereon to vary the amount of said resistance to cause the indication of the indicating instrument to vary accordingly.

9. In a system for determining the location of a railroad train, a stretch of track, track section circuits in said stretch, means in a circuit controlled by said track section circuits as the train passes through the stretch for varying the electrical character- 125 130

istics of said circuit, and an indicating instrument in said circuit responsive to said variations.

10. In a system adapted for determining the location and direction of travel of a railroad train, a circuit including resistances, a source of energy, an indicating instrument, and track circuit means controlled by the train for either adding or subtracting resistances in said circuit, depending upon the direction of travel of the train, to change the readings of said indicating instrument.

11. In a system adapted for determining the location and direction of travel of a railroad train in combination, a circuit comprising resistance, a source of energy and an indicating instrument, train operated circuit controllers arranged so as to be effective to vary the resistance of the circuit to progressively decrease the reading of the indicating instrument for one direction of travel of the train and to progressively increase the reading of the indicating instrument for the opposite direction of travel of the train.

12. In a system for determining the location of a railroad train, a stretch of track, means in a circuit electrically separated from said track, but controlled by the progress of the train over said track for varying the electrical characteristics of said circuit, and an indicating instrument in said circuit responsive to said variations.

13. In a system for determining the location of a railroad train in a stretch of track, a circuit insulated from said track, a source of energy in said circuit, means associated with said circuit, controlled by the presence of the train in said stretch, varying the electric current strength in said circuit, and means in said circuit responsive to the variations in said current strength.

14. In a system for determining the location of a railroad train in a stretch of track, the combination comprising, a circuit electrically isolated from said track, devices associated with said circuit, controlled automatically by the progress of the train through said stretch, varying the electrical characteristics of said circuit, and means in said circuit, responsive to the variations in said electrical characteristics, indicating the location of the train in said stretch.

15. In a system for determining the location of a railroad train, a stretch of track for the train divided into sections, a circuit electrically isolated from said track, devices in said circuit, one for each section, changing the electrical characteristics of the circuit when any of said sections is occupied by the train, and means in said circuit responsive to said electrical characteristic changes.

16. In a system for determining the location of a railroad train, a stretch of track for the train divided into sections, a circuit electrically separated from said track, a device

connected with said circuit for each section, each of said devices, when operated by a train in its section, automatically affecting the electrical characteristics of said circuit differently, and means in said circuit responsive to the changes of the electrical characteristics of said circuit.

17. In a system for determining the location of a railroad train, a stretch of track for the train divided into sections, a circuit insulated from said track, a device associated with said circuit for each section, each of said devices, when operated by a train in its respective section, changing said circuit differently, and means in said circuit responsive to the changes in said circuit.

18. In a system for determining the location of a railroad train, a stretch of track for the train divided into sections, a circuit insulated from said track, means connected to said circuit for each section controllable by a train in said section for changing the characteristics of said circuit, the means for adjacent sections, when controlled, being adapted to affect said circuit differently, and means in said circuit responsive to changes in said characteristics.

19. In a system for determining the location of a railroad train, a stretch of track for the train divided into sections, a circuit electrically separated from said track, a source of energy in said circuit, means connected with said circuit for each section controllable by a train in said section for changing the current in said circuit, the means for adjacent sections, when controlled, being adapted to change said current differently, and means in said circuit responsive to said current and said current as changed.

In testimony whereof, I have subscribed my name.

ALLEN B. KENDALL.
